(57) **CLAIM**

We claim the ornamental design for a switchgear enclosure with a plenum, as shown and described.

DESCRIPTION

FIG. 1 is a front, top and right side perspective view of a switchgear enclosure with a plenum showing our new design; FIG. 2 is a front elevation view thereof;

FIG. 3 is a left side elevation view thereof;

FIG. 4 is a right side elevation view thereof;

FIG. 5 is a rear elevation view thereof;

FIG. 6 is a top plan view thereof; and,

FIG. 7 is a bottom plan view thereof.

The broken line portion of the figure drawings is included to show unclaimed subject matter only and forms no part of the claimed design.
